UNITED STATES PATENT OFFICE.

JEREMIAH A. MOYNIHAN, OF MINNEAPOLIS, MINNESOTA.

CAR-REPLACER.

1,385,571.

Specification of Letters Patent. Patented July 26, 1921.

Application filed October 11, 1920. Serial No. 416,167.

To all whom it may concern:

Be it known that I, JEREMIAH A. MOYNIHAN, a citizen of the United States, residing at Minneapolis, in the county of Hennepin and State of Minnesota, have invented certain new and useful Improvements in Cart-Replacers; and I do hereby declare the following to be a full, clear, and exact description of the invention, such as will enable others skilled in the art to which it appertains to make and use the same.

This invention relates to car replacers of the general type shown in the previous U. S. Patents to applicant Nos. 1,131,941, granted 15 March 16, 1915, and 1,155,431, granted Oct. 5th, 1915, and involves certain improvements in the replacer, in the means for holding the same in place on the ties and in the means for clamping the same to the track. It is an 20 object of this invention to simplify and improve the means for clamping the replacer to the rail.

Another object of this invention is to provide a means providing more secure engagement of the replacer with the railroad ties.

A further object of the invention is to provide such a means for clamping the replacer to the rail that in operation the replacer will tend to become more securely clamped 30 thereto.

It is also an object of the invention to provide a universally reversible car replacer. These and other objects of the invention will become apparent as the description proceeds, in connection with the accompanying drawings, in which like reference characters refer to the same parts throughout, and in which,

Figure 1 is a plan view showing a pair of 40 replacers secured to the rails of the track, a pair of car wheels and an axle connecting the same, being also shown in dotted lines;

Fig. 2 is a view of the replacer in side elevation, as viewed from the left of Fig. 1, also 45 showing a part of the rail;

Fig. 3 is a view in side elevation of the replacer, as seen from the right hand side in Fig. 1, the rail and wheel being shown in dotted lines;

Fig. 4 is a sectional elevation taken on line 50 4—4 of Fig. 3 looking in the direction of the arrows; and

Fig. 5 is a sectional plan taken on line 55 5—5 of Fig. 3, looking in the direction of the arrows.

In Fig. 1, the rails of the track are shown

as 1, the cross ties therefor, as 2, and a pair of replacers A. A pair of car or locomotive wheels 3 connected by axle 4 are shown in dotted lines. A pair of replacers is always 60 used, which replacers are exactly alike in construction. A description of one will therefore suffice. The replacer proper consists of two main portions, the portion 5, which is designed to receive the car wheels, and a portion 6 connected thereto, which is designed to engage the ties. The member 5 comprises a portion 7 of trapezoidal configuration and a triangular shaped portion 8 pivoted thereto, the two portions together constituting a 70 wedge shape member, with substantially continuous side portions. The portion 7 comprises a web 8^a and top and bottom flanges 9 extending along its edges. It also comprises a central rib 10 extending longitudinally thereof and spaced from web 8^a. Two gage members 11 project at the end of this rib and are adapted to engage the side of the track rail, and together with the end portion 12 of member 7, determine the position of the replacer relative to the rail.

The flanges 9 are recessed to provide an entrance for a clamping member 14 to be described. The member 8 forms an approach block upon which the wheels first 85 ride when the car is replaced. This member also has flanges 15 at the top and bottom edges thereof, and is formed with a web 16 appropriately strengthened by transverse ribs 17.

Connected to the member 7 by suitable connecting members 18 is a tie-engaging member 6. This member is also of narrow trapezoidal form and is composed of a lateral web portion 19 surrounded at its edge 95 by a flange 20, and having transverse ribs 21. Projecting from each side thereof above the flange 20, are series of buttressed teeth 21^a. Four of these series are shown on each side, but it will be understood that any desired number may be used and the teeth may be of any desired form. Near the larger end of member 6, a rib 22 of considerable width extends between the flanges 20 and a slot 23 is formed therethrough. Ob- 100 long slots 24 are formed on each side of this rib which communicate with slot 23, and extend substantially to the edge of the flange 20. Disposed within the slot 23 is a bar 25 of slightly smaller dimension than the slot 110 to enable it to slide easily therein. The slot 23 and bar 25 are rectangular in cross section

and the ends of bar 25 are inclined toward the small end of member 6. A pin 26 is carried by bar 25 and projects through the slots 24 to prevent the bar from falling out of the slot 23. This pin also forms a stop to determine the position of the bar 25 when the replacer is in use. As shown in Fig. 2, this member 25 is adapted to abut against the side of the tie to prevent longitudinal motion of the replacer.

When the replacer is placed along side of the rail, it is clamped thereto by a clamping member 14. This member is substantially of channel or U-shape and comprises a portion 26 and two arms 27. The two side members 27 are slightly inclined toward each other as shown in exaggerated form in Fig. 5. As clearly shown in Figs. 1 and 4, in order to clamp the member 7 to the rail, the clamp 14 is placed over the tread portion 28 of the rail and over the rib 10 of the member 7 through the recesses in the flanges 9. The clamp is then moved along the rail and the rib 10 and firmly forced into clamping position. It will be noticed that the clamp moves under the flange 9 and is thus prevented from lifting when the replacer is in use. The clamp 14 is so designed as to dimensions that it can be used with all sizes of rails, there being room on flange 10 for sufficient movement to enable the clamp to clamp any size rail to the flange.

The pivot shown connecting members 7 and 8 is represented as a bolt with a nut thereon. It will be understood, however, that any desired form of pivot, such as a rivet, or other type may be used.

There are also shown in member 6, oblong openings 29, by means of which the device can be lifted or carried by hand, or be handled by means of crane hooks, hand bars, or otherwise.

It will be noted that the replacer described herein is reversible lengthwise, as well as vertically or crosswise. When the device is inverted from the position shown in Figs. 2 and 3, the bar 25 merely drops out on the other side and can be placed in position to abut the tie in the same manner as shown. As stated, the teeth 21 are placed on both sides of member 6.

Referring to the clamping means 14, it will also be noted that as the car or locomotive rolls onto the replacer, the stress occasioned by the impact thereof will tend to move the replacer longitudinally along the rail away from the wheels. With the clamping means shown, this stress will tighten the clamp to more securely hold the replacer against the rail, and thus prevent any longitudinal motion.

From the above description, it is thought the structure and operation of the replacer will be clearly understood. The pair of replacers are clamped to the rail, as shown

in Fig. 1 and the displaced car brought into position for the wheels to ride up the flange of the member 5, and from thence, onto the rail. As set forth in applicant's prior patent, when the wheels first strike the replacer, there is a tendency to throw the other end of the replacer upward, this tendency resulting in great strain being placed upon the parts. This is relieved by having the member 8 pivoted to member 7. The invention consists in the matter shown and described and set forth in the following claims.

What I claim is:

1. A car replacer comprising a member adapted to contact the rail, a longitudinal rib member thereon and a U-shaped wedge member, one of the arms of which engages said rib member, and the other arm of which contacts the opposite side of the rail.

2. A car replacer comprising a member adapted to lie at an angle to and to contact the rail, a longitudinal member carried thereby and a slid able clamp engaging said longitudinal member and embracing the tread portion of the rail.

3. A car replacer having in combination, a car wheel supporting member, a longitudinal member formed thereon, and a slid able channel-shaped clamp, the sides of which are slightly converging longitudinally, adapted to clamp said longitudinal member to the tread portion of the rail.

4. A car replacer having in combination a member having top and bottom flanges, a longitudinal member carried thereby and spaced therefrom, and a slid able clamp adapted to clamp said longitudinal member to the tread portion of the rail.

5. A car replacer comprising in combination, a car supporting member disposed at an angle to the rail, and a slid able clamp adapted to embrace a portion of the member and a tread portion of the rail to clamp the member thereto.

6. A car replacer having in combination, a car wheel supporting member disposed in angular relation to the rail, and a slid able clamp arranged to clamp said member to the tread portion of the rail, and tie abutting means carried by said member.

7. A car replacer having in combination, a car wheel supporting member disposed in angular relation to the rail, and a slid able U-shaped clamp adapted to clamp said member to the tread portion of the rail.

8. A car replacer comprising a car wheel supporting member having a top flange thereon, a longitudinal member carried by said first mentioned member, and a slid able clamp adapted to embrace said longitudinal member and the tread portion of the rail and to lie under said flange when in clamping position.

9. A car replacer having in combination

5 a car wheel supporting member disposed in angular relation to the rail and a channel-shaped clamp, the sides of which are converging, adapted to embrace said member and the tread portion of the rail in such manner that the impact of the car wheels on said member will tend to tighten the clamp.

10. A car replacer having in combination, a car wheel supporting member, a tie-engaging member secured thereto and a thrust member adapted to abut a cross tie slidably carried by said tie-engaging member.

11. A car replacer comprising a tie-engaging member and a slidable dog therein

adapted to form a cross tie abutting member, said dog and tie-engaging member being reversible.

12. A car replacer comprising a car-supporting member adapted to lie at an angle 20 to the rail, an approach member pivoted thereto, a tie-engaging member carrying a tie abutting dog therein, connected to and spaced from the car supporting member, said parts being reversible, both longitudinally and transversely, the replacer being 25 bodily reversible, both longitudinally and transversely.

In testimony whereof I affix my signature.

JEREMIAH A. MOYNIHAN.
